UNITED STATES PATENT OFFICE.

EDGAR A. MCALLISTER, OF BALTIMORE, MARYLAND, ASSIGNOR, BY MESNE ASSIGNMENTS, TO THE MCALLISTER GAS-LIGHT, HEAT AND POWER COMPANY, OF WEST VIRGINIA.

CARBURETER.

SPECIFICATION forming part of Letters Patent No. 645,485, dated March 18, 1900.

Application filed August 29, 1899. Serial No. 728,828. (No model.)

To all whom it may concern:

Be it known that I, EDGAR A. MCALLISTER, a citizen of the United States, residing at Baltimore, in the State of Maryland, have 5 invented certain new and useful Improvements in Carbureters, of which the following is a specification.

This invention relates to carbureting devices in which aeriform fluid is carbureted.

10 Among the objects thereof is to provide an apparatus that will uniformly and permanently carburet aeriform fluid, properly regulate the proportions of the component parts, and produce an effective gas at the minimum 15 of carbon consumption.

In the accompanying drawing the apparatus is shown in section, except the compressor, pipes, and regulating-valves.

The letter A designates a gas-engine arranged with a compression-cylinder a to compress the atmospheric air.

B is the humidity-eliminator, C the carbureter, and D the gasometer.

From the compressor a a pipe E extends to 25 and projects into the eliminator B. In this pipe E is arranged a safety-valve e to discharge any excess of pressure, a regulating-valve e' to govern the amount of pressure in the eliminator, and a diffuser e² to spray the 30 air being discharged into the eliminator. From the eliminator extends the pipe F to the carbureter, into which it projects nearly to the bottom. In this pipe F is a regulating-valve f, which governs the amount of pressure 35 carried in the carbureter, and the lower end of the pipe F is provided with a diffuser c' to spray the air as it enters the hydrocarbon. From the carbureter extends the pipe G to the gasometer, entering the latter at the bottom and projecting above the liquid packing g.

40 In this pipe is arranged a regulating-valve g' to govern the amount of pressure carried in the gasometer. From the gasometer extends the pipe H, which furnishes the supply of gas 45 for consumption and to drive the engine A, the branch pipe h being provided with a governor h' to govern the supply of gas to the engine, said governor being connected by a pipe h² to the pipe E between the regulating-

valve e' and compression-cylinder a in order 50 to regulate the working of the engine in accordance with the amount of pressure carried in the eliminator B.

The engine A may be of any construction and actuated by steam or other suitable 55 means, but in this case I prefer using a gas-engine, as the power therefor can be derived from the product of the apparatus. The compression-cylinder a is of the usual kind, provided with a piston and induction and education valves.

The humidity-eliminator B in this instance consists of a chamber b, in which the aeriform fluid is compressed, and a chamber b', which contains sulfuric acid b⁷ or any suitable 65 absorbent. Between the two chambers is arranged a cut-off valve b⁶ and a properly-constructed check-valve b² to prevent any back-flow of the fluid. At the bottom of the chamber b is arranged an automatic discharge device 70 consisting of a float b³, lever b⁴, and a valve b⁵, the latter being operated when the water eliminated from the air reaches a given height by the float rising, which through the medium of the lever actuates the discharge- 75 valve.

The carbureter C in this instance consists of a chamber c, which contains the hydrocarbon c². The supply-pipe F extends nearly to the bottom of the carbureter and is provided 80 at its lower end with a diffuser c' to spray the aeriform fluid as it is subjected to the hydrocarbon.

The gasometer D is of the usual form, consisting of a fixed tank d and a movable tank 85 d', with suitable liquid packing g to form a gas-tight joint between the two tanks, the supply-pipe d² and the discharge-pipe d³ connecting with the chamber above the packing g.

The safety-valve, check-valve, regulating-valves, and engine-governor are of the usual well-known forms. Therefore a detailed description of the same is unnecessary.

In the operation of the apparatus there being always sufficient gas retained in the gasometer B to start the engine, which is done in the usual manner, the air compressed by the compression-cylinder a passes through

- the pipe E, regulating-valve e' , and diffuser e^2 , where it enters the chamber b of the eliminator B and is confined therein by the cut-off valve b^2 until from thirty to fifty pounds pressure is accumulated, this amount of pressure being sufficient to eliminate or exclude nearly all the humidity from the aeriform fluid, the humidity condensing and accumulating at the bottom of the chamber b , from which after a predetermined amount is accumulated it is discharged by the float rising, which opens the valve b^3 through the intervening lever b^4 . As soon as sufficient water has been discharged to lower the float the valve b^3 is closed. Thus the accumulating water is constantly being disposed of automatically. When the desired pressure is accumulated in the chamber b and the greater amount of humidity eliminated mechanically by the compression, the cut-off valve b^6 is gradually opened, which, allows the aeriform fluid to pass to the chamber b' of the eliminator B, where it comes in contact with the sulfuric acid, which having a great affinity for humidity, entirely eliminates any humidity from the aeriform fluid which might remain therein, leaving the same in condition to freely and uniformly absorb the hydrocarbon and bring the molecules of the aeriform fluid and hydrocarbon in actual contact with each other. From the eliminator B the fluid passes to the carbureter C through the pipe F and diffuser c' at the lower part of the chamber c and expands into the hydrocarbon from thirty pounds pressure to five pounds, (the amount carried in the carbureter,) which being free from humidity effects a uniform and proper amount of hydrocarbon absorption necessary to produce the desired combustion and economical consumption of the hydrocarbon. From the carbureter C the gas passes to the gasometer D, where it is again expanded and retained at about two pounds pressure, but as this second expansion takes place where there is no hydrocarbon to be absorbed the molecular parts although occupying a larger space contains the same amount of hydrocarbon as absorbed in the carbureter. From the gasometer the gas passes to the distributing-pipes ready for consumption.
- In case the compressor is supplying the aeriform fluid faster than the consumption of the gas the increase of pressure in the pipe E acts on the governor h' and regulates the supply of gas to just keep the engine A running. If under this condition the pressure still increases, the surplus over the predetermined amount carried is discharged by the safety-valve e .
- By this apparatus a uniform and economical gas is produced and maintained which will not condense or the component parts thereof separate. The relative proportion of the parts can be accurately regulated to produce gases containing from the minimum to the maximum amount of hydrocarbon, as desired, and the apparatus being practically

self-actuating it requires only the minimum of labor to operate the same, thereby procuring economy both in attendance and consumption of hydrocarbon, the latter being due to the proper proportions of the component parts of the gas, due to the perfect regulation of the apparatus and the process and method therein employed.

Either of the elements disclosed may be greatly modified—that is, by dispensing with, adding to, or changing the form of the parts thereof. Therefore any modifications of the same are included with the claims.

A gasometer is shown and claimed in some of the combinations. It may, however, be dispensed with and the pipe H act as an equivalent. Therefore such pipe is included as the equivalent of the gasometer.

The process herein employed by which the carbureting is accomplished and the method by which the relative proportions of the hydrocarbon and aeriform fluid are regulated I reserve for separate patents, the applications for which were filed August 29, 1899, Serial Nos. 728,829 and 728,830.

Having thus described my invention, what I claim is—

1. In an apparatus for carbureting aeriform fluids, the combination of a carbureter; an air-compressor; and a compressed-air tank having means for removing the water of condensation therefrom.

2. In an apparatus for carbureting aeriform fluids, the combination of a carbureter; an air-compressor; a compressed-air tank; and an automatically-controlled discharge-valve for removing the water of condensation from the said tank.

3. In an apparatus for carbureting aeriform fluids, the combination of an air-compressor; a compressed-air tank having means for removing the water of condensation therefrom; an auxiliary tank communicating with the compressed-air tank; and a carbureter.

4. In an apparatus for carbureting aeriform fluids, the combination of an air-compressor; a compressed-air tank having means to remove the water of condensation therefrom; a regulating-valve between the compressor and compressed-air tank; and a carbureter.

5. In an apparatus for carbureting aeriform fluids, the combination of an air-compressor; a compressed-air tank having means to remove the water of condensation therefrom; a regulating-valve between the compressor and compressed-air tank; a carbureter; and a regulating-valve between the compressed-air tank and the carbureter.

6. In an apparatus for carbureting aeriform fluids, the combination of an air-compressor; a compressed-air tank having means for removing the water of condensation therefrom; a carbureter; a gasometer; and a regulating-valve between the carbureter and gasometer.

7. In an apparatus for carbureting aeriform fluids the combination of an air-compressor; a compressed-air tank having means for re-

moving the water of condensation therefrom; a regulating-valve between the compressor and compressed-air tank; a carbureter; a regulating-valve between the compressed-air tank and carbureter; a gasometer; and a regulating-valve between the carbureter and gasometer.

In testimony whereof I affix my signature in the presence of two witnesses.
